UNITED STATES PATENT OFFICE.

GEORGE W. DRUMHELLER AND CHARLES H. NORTH, OF CLEVELAND, OHIO,
ASSIGNORS OF ONE-HALF TO STANDISH M. YORK, OF SAME PLACE.

MACHINE FOR CUTTING GEAR.

SPECIFICATION forming part of Letters Patent No. 409,776, dated August 27, 1889.

Application filed December 1, 1888. Serial No. 292,420. (No model.)

To all whom it may concern:

Be it known that we, GEORGE W. DRUMHELLER and CHARLES H. NORTH, citizens of the United States, and residents of Cleveland, 5 in the county of Cuyahoga and State of Ohio, have invented certain new and useful Improvements in Gear-Cutting Machines, of which the following is a specification.

This invention relates to machines for cutting gear-teeth; and it consists in the peculiar construction and combination of parts, as hereinafter fully described, and pointed out in the claims.

In the accompanying drawings, Figure 1 is 15 a top or plan view. Fig. 2 is a side elevation, and Fig. 3 is an end elevation, of our new gear-cutting machine. Fig. 4 is a vertical section on line 4 4 on Fig. 2. Fig. 5 is a sectional view of cutting-tool holder and part of 20 a gear-wheel, showing the manner of cutting the teeth.

A represents a standard and base, which support all of the working parts of our machine, to the front end of which is provided 25 a slotted projection A², having a bore for carrying a vertical spindle B. The lower portion of said spindle is screw-threaded, and in the slot a is placed a hand-wheel nut C, in which the said spindle plays. The bore 30 through the projection A² is not screw-threaded.

D is an index feed-wheel fixed on the spindle, having a hub in which a feather or set-screw d is placed, which fits in a longitudinal 35 groove b in the spindle. The top end of this spindle carries the blank-wheel to be cut, and the index-wheel is employed to give slow upward movement for feeding the blank upward, as hereinafter described.

40 A³ is a projection at the upper end of the standard A, and is also bored for supporting the top end of the spindle. The wheel D and its hub is fitted to turn between the two projections A² and A³.

45 E is a slotted plate lying on the top of the standard A. Its forward end is provided with box-bearings e e for counter-shaft F. This plate is held by means of a screw E², passed through the slot and screwed into the top of 50 the standard A. At its rear end is also provided a screw G, passed through a lug g on the top of the standard A, and has two nuts

g² g³—one at each side of the said lug g—the purpose of which is to provide for nice adjustment of the cutting-tool held in the shaft 55 F to its work. On one end of the shaft F is placed a cone driving-pulley P. On the opposite end of the shaft F is fixed a grooved crank-disk H, holding an adjustable wrist-pin p, to which is attached a pitman I. 60

On the side of the standard A and to a rear projection thereof are attached slide-bearings J J, in which a sliding bar K is set. These bearings have adjustment-screws j j. To a slotted projection k on said bar K is attached 65 an adjustable wrist-pin K², to which the pitman I is attached.

To the forward end of the sliding bar K is attached a pawl L, whose forward end engages with the serrated edge of the index-wheel D. 70 A light spring l in the heel of the pawl serves to keep the end of the pawl in contact with the wheel D.

f is the cutting-tool set in a hole through the shaft F, and is secured therein by means 75 of a set-screw s. This tool is so made and set that one end will face the edge of the wheel while the other end cuts the tooth in the edge.

The operations of this machine are as follows: The blank to be cut is secured onto the 80 disk B² by a nut n, and the plate E is adjusted so as to bring the shaft and its cutting-tool up to the edge of the blank. The feed is also adjusted by setting the wrist-pin p in the disk H and the wrist-pin k² in the sliding 85 plate bar K to the required points for giving the necessary play to said sliding bar for operating the pawl L, which moves the index feed-wheel D. This adjustment is determined by the number of teeth desired for the 90 gear-wheel to be cut. Having thus adjusted these parts of the machine, the spindle is run down by turning the hand-wheel nut C so that the rotating cutter will just reach the top edge of the blank. The machine may 95 now be put in motion. The rotating cutter now begins its work by cutting the upper edge of the blank into little curved notches, as seen at x on Fig. 1. At each revolution of the cutter-shaft the feed-wheel is also 100 moved, which turns the blank the width of the tooth to be cut, so that these notches are cut in rapid succession as the said blank is turned. When the blank has turned once

around, it has been fed upward by the spindle B turning in the nut C. Then as the spindle continues to turn the rotary cutter cuts the notches deeper down the periphery 5 of the blank, and so on as the blank is fed upward the teeth are gradually cut in the said periphery. The index feed-wheel D brings the notches previously cut squarely 10 opposite the cutting-tool, so that the teeth are cut gradually through from the upper to the lower side of the blank, as seen in the diagram, Fig. 5, the tool moving in the direction indicated by the arrow. Thus the bottoms of the spaces between the teeth are cut straight 15 across, as well as the outer edges of the teeth. It will be seen that it makes no difference what the thickness of the blank may be, the teeth are all cut alike, and, if desired, two or more blanks might be placed one above 20 another on the disk B² and all cut before removing them; thereby facilitating the work.

Having described our invention, what we claim, and desire to secure by Letters Patent, is—

25 1. In combination, the vertical spindle B, supported in bearings A² A³ of standard A and having blank-holder B², and the rotating shaft F, having cutting-tool f and journaled in bearings e e of adjustable plate E, which 30 is provided with clamping-screw E², and the adjusting-screw G and nuts g g, by which said shaft and cutting-tool may be adjusted for cutting different sizes of gear-wheels.

2. The combination, with the rotating shaft 35 F, of the cutting-tool f, having one end provided with square cutting-edge for facing the periphery, and the other end provided with end and side cutting-edges for cutting teeth

in the periphery of the blank, substantially as specified.

3. In combination, the spindle B, supported in bearings A² A³ on standard A, and having the index-wheel D attached, also having the hand-wheel nut C attached and located between the bearings A² A³, the spindle being 45 screw-threaded, so that when rotated by the index-wheel it will also be moved upward through said nut, substantially as and for the purpose specified.

4. The combination, with the spindle B, supported in bearings A² A³ of the standard A and provided with index-wheel D and nut C, of the rotary shaft F, having the crank-disk H attached, the pitman I, connecting said disk H with sliding bar K, playing in bearings J J on the side of the standard and having pawl L engaging with the index-wheel D, for imparting intermittent rotative motion to the spindle, substantially as and for the purpose specified.

5. The combination, with standard A, of the adjustable plate E, provided with the bearings e e for the rotating tool-holding shaft F, having the crank-disk H, and the pitman I, adjustably connected with the sliding bar K, 65 playing in the bearings J J on the side of the standard A and provided with pawl L, engaging with the index-wheel D, whereby the tool-holding shaft may be adjustably set in relation to the blank-holder, substantially as 70 described, and for the purpose specified.
